UNITED STATES PATENT OFFICE.

RICHARD P. GOURLEY, OF SPRINGFIELD, AND HAROLD P. PARTENHEIMER, OF CHICOPEE FALLS, MASSACHUSETTS, ASSIGNEES TO THE FISK RUBBER COMPANY, OF CHICOPEE FALLS, MASSACHUSETTS, A CORPORATION OF MASSACHUSETTS.

DESIGN FOR A TIRE.

57,637.

Specification for Design.

Patented Apr. 26, 1921.

Application filed September 28, 1920. Serial No. 413,410. Term of patent 14 years.

To all whom it may concern:

Be it known that we, RICHARD P. GOURLEY, a citizen of the United States, residing at Springfield, county of Hampden, and State of Massachusetts, and HAROLD P. PARTENHEIMER, a citizen of the United States, residing at Chicopee Falls, county of Hampden, and State of Massachusetts, have invented a new, original, and ornamental Design for a Tire, of which the following is a

specification, reference being had to the accompanying drawing, forming part thereof.

Figure 1 is a plan view showing a portion of a tire casing embodying our design; and

Fig. 2 is a section on line 2—2 of Fig 1.

We claim—

The ornamental design for a tire as shown.

RICHARD P. GOURLEY.
HAROLD P. PARTENHEIMER.
